(57) **CLAIM**

The ornamental design of a radiation detector, as shown and described.

DESCRIPTION

FIG. 1 is a perspective view of a radiation detector showing the claimed design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The present design is directed to a device that detects radiation and converts and outputs it into a video image, and is used in hospitals (radiography, dentistry, surgery, etc.) and industrial inspection equipment.

The broken lines shown in the drawings depict portions of the radiation detector and form no part of the claimed design.
